UNITED STATES PATENT OFFICE.

WADIM ARSCHAULOFF, OF PARIS, FRANCE.

MEAN EFFECTIVE PRESSURE INDICATOR FOR INTERNAL-COMBUSTION ENGINES.

Application filed November 29, 1921. Serial No. 518,685.

To all whom it may concern:

Be it known that I, WADIM ARSCHAULOFF, a Russian subject, and a resident of Paris, in the Republic of France, have invented 5 certain new and useful Improvements in Mean Effective Pressure Indicators for Internal-Combustion Engines, of which the following is a specification.

This invention relates to an apparatus for 10 indicating the mean effective pressure in internal-combustion engines and has for its object to facilitate the supervision of multi-cylinder engines by enabling the supervisor to readily perceive at any time the mean 15 effective pressure in each cylinder, thus avoiding the necessity of taking numerous indicator diagrams in order to ensure that the power developed is equally distributed throughout the several cylinders.

20 The improved indicator is applicable to any type of internal combustion engine having a fixed cycle and is particularly applicable to Diesel engines which have a typical indicator diagram.

25 The indicator comprises a closed vessel or chamber in constant communication through a small orifice or narrow bore tube with the compression and combustion chamber of the cylinder. When the engine is working, 30 therefore, a certain pressure will gradually arise in the vessel and the variation of this pressure can be reduced by increasing the capacity of the vessel or by reducing the bore of the orifice or connecting tube. The 35 pressure in the vessel will be dependent on the mean effective pressure in the cylinder.

In order that the invention may be more

clearly understood reference is hereinafter

made to the accompanying drawings where-

40 on:-

Figs. 1 and 2 are diagrams illustrating the compression and expansion when the cylinder is working almost without combustion.

Figs. 3 and 4 are corresponding diagrams 45 when the cylinder is working at full load.

Fig. 5 is a vertical section and Fig. 6 a face view of one form of indicator according to the present invention.

Fig. 7 illustrates a modification thereof.

50 The relation of the pressures in the cylinder and vessel may be calculated, by way of example, for a two-stroke Diesel engine.

Assuming that the compression pressure is 32 atmospheres from a polytrope having 55 the exponent index 1.35, then $P_w^{1.35}$ —a constant. Two cases may be taken (1) when

the cylinder is working almost without combustion, when the mean effective pressure is zero and the expansion line coincides with the compression line and (2) when the cylinder is working at full load and a mean effective pressure of 7 atmospheres.

The first case is illustrated by the diagrams in Figs. 1 and 2. Fig. 1 shows the compression line a, b, c and the expansion line c, b, a obtained with a mean effective pressure P equal to zero.

In the diagram shown in Fig. 2, the same compression and expansion lines are plotted as time abscissa and pressure ordinates.

It can be assumed with a fair degree of accuracy that in passing through a very narrow-bore tube the weight of gas periodical- 75 ly passing through the tube in both direc- tions between the cylinder and vessel corre- sponds to the time and pressure differences in the cylinder and in the vessel. Conse- quently a mean pressure gradually arises in the vessel. If the area a, b, c, b, a of Fig. 2 is distributed over its length, a value of 80 approximately 5.2 atmospheres is obtained. That is to say, whilst the mean effective pres- 85 sure P in one cylinder of the two-stroke Diesel engine is zero, the pressure in the ves- sel is approximately 5.2 atmospheres.

The second case is illustrated by the dia- 90 grams in Figs. 3 and 4 where the cylinder generates its full power with a mean effec- tive pressure $P=7$ atmospheres.

Proceeding as in the first case, one obtains a pressure of about 8.1 atmospheres in the vessel for a mean cylinder pressure of 7 atmospheres. In this manner a complete pres- 95 sure diagram is obtained.

These theoretical calculations have been verified by numerous actual tests with sub- 100 stantially identical resultant figures.

From the foregoing, it is apparent that the diaphragm or Bourdon tube of the gauge on the vessel must have an initial tension 100 such that the pointer only leaves the zero mark of the scale at a pressure in the vessel of 5.2 atmospheres, corresponding to the zero cylinder pressure. The scale should be so graduated that, for pressures between 5.2 and 8.1 atmospheres in the vessel, the pointer 105 traverses from zero to 7 on the scale. The pointer must register with the mark 7 when the pressure in the vessel is 8.1 atmospheres. The gauge therefore indicates the mean effec- 110 tive pressure in the cylinder and not the pressure in the vessel. Where the pointer is

actuated by the tube of a Bourdon gauge, for instance, the tube may be given an initial tension by means of a relatively stationary set screw bearing radially against the free end of the tube and on the inner side thereof.

The scale must be similarly graduated for other types of internal combustion engines. The graduations are preferably verified by taking diagrams from the engine.

Figs. 5 and 6 illustrate the construction of the indicator. The vessel 1 is in constant communication with the combustion chamber of the cylinder through a very narrow-bore tube 3. The tube may be replaced by any other means adapted to considerably restrict the gas passage. The gauge 2 is fitted with a scale graduated as above described and indicates not the pressure in the vessel 1 but the corresponding mean effective pressure in the cylinder.

Fig. 7 illustrates a modification of the indicator in which the vessel 1 is fitted with a small safety valve 4 in order to avoid damage to the gauge by excessive rise of pressure in the vessel 1 should gas or air under high pressure remain in the cylinder when the engine is at rest.

Claims:

1. A mean effective pressure indicator for internal combustion engines comprising a closed vessel having restricted communication with the combustion chamber of the engine cylinder, and a pressure gauge communicating with said vessel and graduated to register the mean effective pressure in the engine cylinder and not the pressure in the vessel.

2. A mean effective pressure indicator for internal combustion engines comprising a chamber having restricted and continuous communication with the combustion chamber of the engine cylinder, a pressure gauge in communication with said chamber, an index pointer, a scale over which said index pointer is adapted to travel and means for actuating said index pointer by the variations of pressure in said chamber, said means being initially under tension so that the pointer only leaves the zero mark of the scale at a pressure corresponding to zero cylinder pressure.

In testimony whereof I hereunto affix my signature.

WADIM ARSCHAULOFF.
